UNITED STATES PATENT OFFICE.

HARRY M. COOPER, OF OAK PARK, ILLINOIS.

SELF-LOCKING SEAL.

1,160,856.

Specification of Letters Patent. Patented Nov. 16, 1915.

Application filed July 2, 1915. Serial No. 37,697.

To all whom it may concern:

Be it known that I, HARRY M. COOPER, a citizen of the United States, and resident of Oak Park, in the county of Cook and State 5 of Illinois, have invented certain new and useful Improvements in Self-Locking Seals, of which the following is a specification.

My invention relates to seals, and more particularly to such as may be employed as 10 tell-tale devices adapted to show whether the articles to which they are secured have been tampered with; and in that general 15 class it relates more particularly to such as have interlocking elements for giving the device its sealing character.

The general object of seals of this class is to show whether the car doors, vehicles, or any relatively movable or separable parts, or packages sealed thereby have been opened 20 or tampered with.

The principal object of the present improvements is to provide a device whereby this general object is effectively attained.

A specific and important object is to provide 25 a seal of strong and simple construction of the general character described which is not susceptible of being opened, unlocked, or "picked," as by unauthorized persons desiring to remove and replace the seal, or if at 30 all so susceptible, then only by such great difficulty, refinement and nicety of operations as to render the device free from such objection for all practical purposes.

A further specific object is to provide a 35 seal which, not being practically susceptible of being "picked" or unlocked, becomes so mutilated when opened by breaking strains as to render the tampering obvious to the casual inspector and also preventing the seal 40 thereafter from performing its sealing function.

Other objects and advantages will appear hereinafter.

In the accompanying drawings, which 45 form a part of this specification, I have illustrated a preferred embodiment of a seal providing the advantages hereinabove pointed out, in which drawings—

Figure 1 shows the device complete as 50 when in use; Fig. 2 is a face view of the blank from which the seal is made; Fig. 3 is a fragmentary view of the housing of the seal partially bent or folded and scored for weakening the same; Fig. 4 is a fragmentary 55 perspective of the hook end of the seal on an enlarged scale; Fig. 5 is a broken, me-

dial, longitudinal section of the device, the hook end being shown in full; Fig. 6 is a fragmentary medial section showing the hook end of the seal interlocked in the housing end, the hook end again being shown in full; Fig. 7 is a transverse section through the device of Fig. 6 as on the line 7—7 thereof in the direction of the arrows; and Fig. 8 is a fragmentary perspective of the interlocked ends of the seal after breaking strains have been brought to bear upon it, the parts being only partially separated.

The blank 10 is ordinarily formed of thin and flexible material, suitably tin plate. 70 The housing end has body portions 11 and 12 adapted to form side walls of the box or housing, these portions having respectively the wings or ears 11^a and 12^a adapted to be folded interlockingly upon each other, as 75 well shown in Fig. 7. Before the side walls are thus locked together, however, the portion 13 is folded through an angle of 180° on the line a—b (Fig. 2) and the projecting portion 14 is turned up substantially at 80 right angles to the portion 13 on the line c—d of Fig. 2, as shown in the sectional views. The body portion 11 is stamped up or indented transversely, as at 15, to provide a recess to accommodate the outer end portion of the projecting part 14 and hold the same securely against pulling strains brought to bear upon it. The portion 14 thus constitutes a transverse wall within the 85 box or housing. This transverse wall 14 90 may be further held against normal pulling strains when the device is in use by the small tabs or wings 17 which are folded over upon the wall 14, as shown in Fig. 3. The wall 14 has the aperture 18 to receive 95 the locking means provided at the other end of the strip. By cutting the wings 12^a and 13^a on an angle substantially as illustrated in Fig. 2 the box or housing is deeper at one end than at the other, as illustrated, by 100 which construction the opening 20 of the housing adapted to receive the hook end of the device may be only deep enough to admit that end portion while the inner compartment 21 may be deep enough to permit 105 the hooks to spread relatively widely after passing through the opening 18.

In my preferred construction the hook end of the device is preferably slotted or cut longitudinally, as at 22, and the portions 23 thus formed are preferably bent in 110 opposite directions to form the hooks 23^a,

one of these hooks lying on one side of the strip 10, the other lying on the other side. The hooks 23^a are formed to lie away from the plane of the strip 10 so that when they 5 are passing through the opening 18 they will be forced toward the plane of the strip at the hooks, and after passing through the opening 18 they will spring away from the plane of the strip there and interlock with the wall 14, as illustrated in Fig. 6, thus 10 locking the hook end of the device securely within the housing. In this connection it is pointed out that the end wall 24 of the housing is quite close to the extremities 25 of the hooks respectively, which provision is important in preventing the strip from being forced farther into the box or housing than is practically sufficient to enable the hooks 23^a to become interlocked, thus increasing 15 the difficulty of "picking" the seal. A transverse crimp or bend 26 is formed in the hook end portion whereby the opening 20 of the housing is substantially filled when the ends are interlocked and it is thus made 20 practically impossible for one to insert a tool for releasing the hooks 23^a. When the seal thus formed is locked and strong pulling strains are brought to bear upon it, as 25 when the device is normally in use and it is desired to break the seal, the hooks 23^a buckle and crumple upon themselves respectively and a mass of such crumpled up material is formed about the opening 18 making 30 a head of upset and overlapped material which cannot be drawn through the opening 18, and breakage of the metal must occur in order to separate the two ends of the seal. In order to avoid unauthorized breakage and the subsequent insertion of the broken 35 end within the housing to preserve the semblance of a seal unbroken I cut or score preferably the body portion 11 contiguous to the strip portion 10 as at 30, thus weakening the side wall 11 at that place so that when strains insufficient to break the hooks 40 23^a are brought to bear upon the device a portion of the wall 11 will be broken out and torn away from the rest of the device, as partially illustrated in Fig. 8. When so broken the outer and visible portions of the seal are so mutilated that the most casual inspection will readily reveal any attempt to 45 conceal the breakage, and with the wall 11 thus broken out the sealing function of the device is destroyed. The scoring or cutting, as at 30, may be done by means of a sharp stamping tool, severing the metal partially but leaving it strong enough to withstand rather severe strains. The directions and 50 extent of such cutting or weakening may be varied. The wall 11 where so cut, however, is weaker than the hook or hooks interlocked with the wall 18 and gives way before any other part of the device breaks. In practice a strong pull or yank with a bail hook

or rod held by the two hands is necessary to break the device. This feature of the weakened wall is applicable to various kinds of such seals and is claimed in my copending application Serial No. 32,048, filed June 4, 73 1915. The cutting of the blank, folding, scoring, etc., may be done according to practices well understood in the art of forming such light metal articles and requires no detailed description. 75

While I have illustrated and described a preferred embodiment of these improvements, the same are susceptible of modification without departure from the spirit of the disclosure herein made, and all such 80 changes and modifications are contemplated by me as fall within the scope of the appended claims.

I claim:

1. A locking seal comprising a strip of 85 flexible material having a hook formed at one end thereof and a relatively flat box-like housing integral with said strip at the other end thereof, said housing having an opening 90 to receive the end of the strip having said hook, said housing having a transverse wall integral with a portion of the housing body within the same and intermediate the ends thereof for engaging said hook interlocking when the hook end of the strip is inserted through said opening and normally 95 into said housing, said transverse wall having an opening through which said hook may pass.

2. A locking seal comprising a strip having one end thereof divided longitudinally and formed into a pair of hooks extending on opposite sides of said strip at the end thereof, the other end of said strip being formed with body portions adapted to overlie each other and to be secured together at edge portions thereof to provide a relatively flat housing having an opening therein for the insertion thereinto of said hooks, said housing having a transverse wall intermediate the ends thereof, said wall having an opening to receive said hooks, said hooks being adapted to spring apart after passing through the opening in said wall and to engage said wall locking when so sprung 115

3. A locking seal comprising a strip of flexible material having locking means at one end portion thereof and a box-like housing integral with said strip at the other end thereof, said housing having an opening to receive the end of the strip having said locking means, said housing having a transverse wall integral with a portion of said housing within the same and intermediate the ends thereof for engaging said locking means interlocking when the end of the strip is inserted through said opening and normally within the housing, said transverse wall having an opening through which said end 130 135

of the strip may pass, said housing having a closed end so spaced from said transverse wall that when the end of said strip is passed through the opening in said transverse wall just far enough to provide the interlocking of said locking means with said transverse wall, the end of the strip substantially contacts the closed wall of the housing whereby the end of the strip is locked against movement both inward and outward with respect to said housing.

4. A locking seal comprising a strip of thin and flexible material having a pair of oppositely disposed hooks at one end thereof and an integrally formed housing at the other end thereof, said housing having an opening to receive said hooks, and having an apertured transverse wall within the housing to engage said hooks, said housing being substantially deeper at the end thereof opposite said opening than at said opening whereby said hooks after passing through said opening and through the aperture in said wall and being pressed in a direction toward each other thereby may spring away from each other materially within said housing.

5. A locking seal comprising a strip of thin and flexible material having a hook at one end portion thereof and an integrally formed housing at the other end portion thereof, said housing having an opening to receive said hook end of the device, an integrally formed and apertured transverse wall within said housing adapted to engage

said hook lockingly to prevent retraction thereof when the hook end of the device is inserted normally into said housing and through the aperture of said wall, a wall of said housing being indented to accommodate a portion of said wall and hold same securely.

6. A locking seal comprising a strip of thin and flexible material divided longitudinally at one end portion thereof and there formed into oppositely disposed hooks, the other end of said strip having body portions secured together to form a housing having an opening toward the hook end of the device, said housing having an integrally formed transverse wall apertured to receive said hooks, a wall of said housing being indented to accommodate a portion of said transverse wall to hold the same securely, the opening in said transverse wall and the normal form of said hooks being such that when the hook end of the device is inserted in said housing and passed through the opening of said transverse wall the ends of said hooks respectively will be pressed toward the plane of the strip at the hooks, the ends of said hooks respectively being adapted to spring away from such plane after passing through the opening of said transverse wall, said transverse wall engaging said hooks lockingly when so sprung apart.
